(57) **CLAIM**

The ornamental design for a container with a cone-shaped base, as shown and described.

DESCRIPTION

FIG. 1 is a forward lower perspective view of a container with a cone-shaped base according to an embodiment;

FIG. 2 is a side view thereof;

FIG. 3 is a cross-sectional side view thereof;

FIG. 4 is a top view thereof; and,

FIG. 5 is a bottom view thereof.
